UNITED STATES PATENT OFFICE.

FREDERICK W. BARNES, OF ROCHESTER, NEW YORK, ASSIGNOR TO EASTMAN KODAK CO., OF ROCHESTER, NEW YORK, A CORPORATION OF NEW YORK.

TRIPOD.

1,007,322.

Specification of Letters Patent. Patented Oct. 31, 1911.

Application filed June 14, 1910. Serial No. 566,728.

To all whom it may concern:

Be it known that I, FREDERICK W. BARNES, of Rochester, in the county of Monroe and State of New York, have invented 5 certain new and useful Improvements in Tripods; and I do hereby declare the following to be a full, clear, and exact description of the same, reference being had to the accompanying drawings, forming a part of 10 the specification, and to the reference-numerals marked thereon.

The present invention relates to tripods such as are used for supporting photographic and other instruments, and it has 15 for its object to provide a folding or collapsible device of this character which will be light, strong and durable, and yet so constructed as to permit its production at low cost.

20 A further object of the invention is to so form and arrange the interlocking parts of the leg sections as to render them capable of being easily assembled and also readily accessible for purposes of repair and adjustment.

25 To these and other ends the invention consists in certain improvements and combinations of parts, all as will be hereinafter more fully described, the novel features being pointed out in the claims at the end of the specification.

In the drawings: Figure 1 is an elevation of a tripod constructed in accordance with and illustrating one embodiment of my invention, one of the legs being in retracted position and the upper or larger section of one of the others being shown in longitudinal section; Fig. 2 is a detail perspective view of the locking spring with adjacent 30 parts of the section by which it is carried being broken away; Fig. 3 is a longitudinal section through the locking device with the adjacent ends of both of two coöperating sections upon which it acts; and Fig. 4 is an elevation of the cradle into which the legs are folded, the view being in section through the latter.

40 In the tripod illustrated, each leg is composed of four telescoping sections, 1, 2, 3, 4, 50 the larger or containing section 1 being at the top and pivoted at 5 to suitable attaching portions on the under side of the supporting head or table 6 that carries the member 7 for holding the camera or other instrument on the tripod. The lower or 55 smaller section 4 is provided at its lower end

with a suitable ground engaging spur 8, as usual. The sections are extended for use as shown in Fig. 1, or the smaller ones may be contracted within the larger holding section 1, as shown by the condition of one of the legs in the same figure. This section carries a cradle 9 comprising in the present instance a pair of transversely extending plates connected by an attaching band 10 60 and provided with depressions 11 forming seats for the other two legs in addition to the seat 12 permanently occupied by the carrying leg. A strap 13 encircles all three legs when folded into their seats, as shown 65 in Fig. 4, one end 14 thereof being permanently attached to the cradle, while the outer free end 15 is provided with a suitable securing device 16 so that it may be detachably secured thereto and temporarily hold 70 the parts together.

The sections are tubular in form and the lower ends of all but the small section 4 are preferably restricted or so formed as to provide an interiorly arranged abutment 17 75 with which coöperates an exteriorly arranged abutment 18 on the adjacent upper end of the next smaller section. This abutment 18 is constituted by a short tubular sleeve encircling the end of the smaller section and held by a pin 19 passed through the latter and the sleeve, as clearly shown in 80 Fig. 3.

Within the same end of the section carrying the sleeve is a tubular thimble 20 that 85 is also held by the pin 19 and the lower end 21 of which forms an abutment to limit the inward or telescopically folding movement of the next smaller section, while within the thimble is looped a leaf spring 21^a, the 90 arms 22 and 23 of which extend longitudinally of the walls of the thimble and are pierced and held by the pin 19. This spring operates a locking abutment 24 preferably carried on the end of one arm thereof, to 95 normally actuate it through a slot 25 in the thimble and an opening 26 in the carrying section to a position in which it coöperates with the end of the larger section, as shown 100 in Fig. 3. To disengage the locking abutment it is simply pressed inwardly with the thumb and held until the movement of its receiving section.

105 The advantages of the simple arrangement described are apparent. In assembling, the sleeve 18, thimble 20, and spring

21 are slipped to their positions on the end of the section and the pin 19 common to all driven through registering openings therein. If any injury or derangement occurs in 5 this group of interlocking parts, the smaller section is thrust inwardly entirely through the adjacent larger section and the said group is then conveniently exposed for the removal of the pin 19 by a punch or otherwise so that any part can be substituted with 10 a new one or quickly withdrawn and placed.

The attaching portion of the upper section 1 is preferably in the form of a head 15 27 into which the end of the section is threaded so that by unscrewing it the next smaller section 2 may be passed through and, after the parts 18, 20, 21 are removed from the latter, the next smaller section 3 20 may, in turn, be passed through it, as described, and so on, a reversal of the procedure outlined being followed in assembling.

I claim as my invention:

25 1. In a tripod leg, the combination with two telescoping tubular sections the larger of which has an interiorly arranged abutment near one end, of a sleeve on the outer side of the adjacent end of the smaller section 30 coöperating with the abutment to limit the outward relative movement of the sections and a pin extending through the sleeve and from side to side through the smaller section to hold them together the pin carrying 35 portion of the smaller section being adapted to be projected from the opposite end of the larger section.

2. In a tripod leg, the combination with 40 two telescoping tubular sections, the larger of which has an interiorly arranged abutment near one end, of a sleeve on the outer side of the adjacent end of the smaller section coöperating with the abutment to limit the outward relative movement of the sections, a thimble arranged within said end and adapted to coöperate with the end of the next smaller section to limit the inward movement thereof and a securing device extending through the sleeve, from side to side 45 through the section and through the thimble to hold them together the portion of the section carrying the securing device being adapted to be projected from the opposite end of the upper section.

50 3. In a tripod leg, the combination with two telescoping tubular sections, the smaller of which is provided with an opening near one end, of a yoke shaped leaf spring looped within said end with its arms lying against 55 the opposite walls thereof, a fastener extending through the tube from side to side and through the arms of the spring and a locking abutment operated by the spring

through the opening to coöperate with the larger section, and prevent inward relative 65 movement of the sections.

4. In a tripod leg, the combination with two telescoping tubular sections, the smaller of which is provided with an opening near one end, of a leaf spring looped within said end, a locking abutment operated thereby through the opening to coöperate with the larger section and prevent inward relative movement of the sections and a securing pin passing from side to side through both arms 75 of the spring and through the section by which it is carried the pin carrying portion of the smaller section being adapted to be projected from the opposite end of the larger section. 80

5. In a tripod leg, the combination with two telescoping tubular sections the smaller one of which is provided with an opening near one end, of a tubular thimble within said end forming an abutment to limit the 85 inward movement of the next smaller section, a leaf spring looped within the thimble, a locking abutment operated thereby through the opening to coöperate with the larger section and prevent inward relative 90 movement of the sections and a securing device extending through both arms of the spring, the thimble and from side to side through the section by which both are carried. 95

6. In a tripod leg the combination with two telescoping tubular sections the larger of which has an interiorly arranged abutment near one end, of a sleeve on the outer side of the adjacent end of the smaller section coöperating with the abutment to limit the outward relative movement of the sections, a tubular thimble within said end of the sleeve carrying section forming an abutment to limit the inward movement of the next smaller section, a spring within the thimble, a locking abutment operated thereby through an opening in the wall of one of the sections to coöperate with the other section and prevent inward relative movement of the sections 105 and a securing pin common to the spring, the thimble, the carrying section, and the sleeve, having its end exposed on the outer surface of the latter. 110

7. The combination with a folding tripod 115 having a plurality of legs, of a cradle carried by one of said legs and having seats for the reception of the others when in folded position and a strap having one end permanently attached to the cradle and the other adapted to encircle all the legs and to be detachably secured to the cradle. 120
